UNITED STATES PATENT OFFICE.

WILLIAM McCLOVE, OF SCRANTON, PENNSYLVANIA, ASSIGNOR TO McCLOVE-BROOKS COMPANY, OF SCRANTON, PENNSYLVANIA, A CORPORATION OF PENNSYLVANIA.

ANTHRACITE-BURNING GRATE FOR FURNACES.

1,105,572.

Specification of Letters Patent:

Patented July 28, 1914.

Application filed March 21, 1913. Serial No. 755,939.

To all whom it may concern:

Be it known that I, WILLIAM McCLOVE, a citizen of the United States, and resident of Scranton, in the county of Lackawanna 5 and State of Pennsylvania, have invented certain new and useful Improvements in Anthracite-Burning Grates for Furnaces; and I do hereby declare the following to be a full, clear, and exact description of the 10 same, reference being had to the accompanying drawings, forming part of this specification, and to the figures and letters of reference marked thereon.

Many attempts have been made to produce 15 a furnace grate for burning the finer grades of anthracite coal and the present invention is designed to overcome certain defects found to exist in the grates heretofore constructed, and to accomplish certain desirable objects, 20 as will hereinafter appear, and incidental both to the manufacture of the grates and to the operation of the same.

In the accompanying drawings,—Figure 1 is a sectional view, in a vertical plane from 25 front to rear, of a grate embodying the present improvements. Fig. 2 is a top plan view of the dumping sections and bearer bars for the same, shown in Fig. 1, the caps being omitted from two of the sections. Fig. 3 is 30 a detail section on an enlarged scale showing one of the dumping sections. Fig. 4 is a top plan view of the four-cap pieces shown in section in Fig. 3. Fig. 5 is an elevation of a portion of one of the dumping sections. 35 Fig. 6 is a detail section of a portion of the dumping section on substantially the line 6—6 of Fig. 3, this view also showing one half of one of the bearer bars.

Like letters of reference in the several 40 figures indicate the same parts.

The grate of the present invention, like 45 grates heretofore constructed, is composed of a series of pivoted sections journaled in bearer bars such as indicated in Figs. 1 and 2 by the letter A, said bearer bars being in turn supported from the setting and walls of the furnace.

Each dumping section of the grate of the 50 present invention is made large as compared with sections of grates as heretofore constructed and each section comprises a rigid frame formed by a plurality of socketed bars arranged parallel to each other and longitudinally of the axis on which the section turns; said bars being connected at their ends

by suitable end pieces. Each end piece is provided with a journal adapted to take a bearing in the bearer bars. The socketed bars of the sections are adapted for the reception of relatively small fuel bearing 60 caps, each independent of the others but so constructed and arranged as to provide for a practically uniform admission of air throughout the whole grate area and also to provide a maximum area of smooth fuel bearing 65 surface over which the tools and implements for manipulating the fuel on the grate may be dragged without liability of catching. Owing to the individually small areas of 70 each of the fuel bearing caps, the evils and difficulties heretofore encountered because of the growth of the metal are practically eliminated.

As shown in the drawings, each of the dumping sections embodies longitudinally 75 extending socketed bars B connected by end pieces B' and intermediate brace pieces B'', the whole constituting a rigid grid or framework which may be proportioned to withstand all the strains to which the section 80 may be subjected in use and at the same time be made relatively light so as to economize in the weight of the material used, as well as to facilitate the handling and manipulation of the section. Each section 85 preferably has four of the socketed bars B and is therefore of considerable width, in actual practice preferably about eighteen inches, and each of the end pieces B' is provided with a journaled projection b adapted 90 to seat in bearings in the bearer bars A, all as will be best understood by reference to the left hand portion of Fig. 2, where two of the sections are shown with the fuel bearing caps removed. 95

The sockets shown at C in Fig. 2 are elongated longitudinally of the bars B and are adapted for the reception of flat shanks d of fuel bearing caps D, the caps being held firmly in place by wrought iron projections d' which are bent over on the under side of the bars B in the well understood manner.

The fuel bearing face of each of the caps is preferably rectangular, as shown in the enlarged view, Fig. 4, and at the right hand side of Fig. 2, and each section is provided with relatively narrow slots or openings for the passage of air through the caps to supply the necessary oxygen for combustion. The 110

caps are separated from each other by spaces which are preferably only as wide as the slots or openings before referred to, the whole area of the air openings in the fuel 5 supporting surface being a relatively small percentage of the total area, but uniformly distributed in the same. As shown, the right hand cap in Figs. 3 and 4 and the two intermediate caps are provided with 10 edge slots E directly facing the unbroken edges of the adjacent caps and with openings E', which do not extend to the edges of the caps in either direction. The left hand cap shown in the two figures men- 15 tioned constitutes one of the edge caps of the dumping section and inasmuch as it is not desirable to have edge slots extending into a free space, or into spaces between the caps in proximity to other edge slots, 20 this cap is provided with openings E² instead of edge slots corresponding to the slots E. One edge of each of the adjacent caps extending longitudinally of the dumping sections is provided with edge slots F best 25 seen in Figs. 2 and 4, from which construction it follows that each of the spaces between caps has opening into it edge slots through the caps on one side but in no space will there be found oppositely disposed edge 30 slots, thus providing for a maximum fuel supporting surface with the admission openings for the air narrow and so distributed that no portion of the fuel resting on the surface will be prevented from receiving 35 all of the oxygen necessary for complete combustion. The narrow edge slots and openings prevent the escape of fuel before the same is reduced by combustion to fine ashes and the dumping sections provide a 40 ready means whereby cinders and clinkers may be discharged.

It will be understood especially from an inspection of Figs. 3, 5 and 6 that the edge slots and intermediate elongated openings 45 in each of the cap sections flare downwardly, whereby the lodgment of any ashes which will pass through the top of the slots and openings is effectually prevented.

The desired construction of fuel bearing 50 surfaces for each of the dumping sections removes the fire sufficiently far from the bars of the section frames to prevent injurious action of heat and combustion on said bars and the fuel bearing caps which 55 are subjected to the most injurious action of the fire are individually small, thus preventing distortion by the cumulative effect of the growth of the iron when in long connected sections and each of said caps may 60 be readily removed and renewed should the same become broken or worn out in use.

The particular shape of the edges of the outside caps of each section is better illustrated in Figs. 1 and 3 and is designed to 65 prevent the effect of growth tending to

cause the sections to become inclined by reason of their overlapping edges striking each other and also to prevent interference with the hoe or implements used in manipulating the fuel on the grate. The particular 70 shapes adopted, however, are not now novel having been embodied in patents heretofore granted to me, but are advantageous even where the injurious effect of growth of the metal is slight, as in the grate of the present 75 invention, for the level position of the sections is assured and the escape of any unconsumed fuel between the sections is prevented because of the fact that the sections 80 may be brought into such close proximity 85 and one may slightly overlap the other without causing difficulties in either the manufacture or the use of the grate.

The frame of each dumping section is 90 preferably provided with a downwardly extending arm H to which the links I and control rods J are pivotally connected as has heretofore been proposed in grates of 95 this kind, but it will be understood that any suitable means may be provided for manipulating the dumping sections in accordance with known practice.

Having thus described my invention, what I claim and desire to secure by Letters Patent of the United States is,

1. In a grate for burning fine fuel, the combination with the bearer bars, of dumping sections journaled in the bearer bars and each embodying a plurality of socketed bars extending longitudinally of the axis 100 of the section, each socketed bar having mounted therein a series of independent fuel bearing caps, said caps being rigidly supported in fixed relation to each other throughout the entire section and each having therein a plurality of elongated air admission openings and a plurality of elongated edge slots extending through the fuel bearing surface.

2. In a grate for fine fuel, the combination with the bearer bars, of dumping sections journaled in said bearer bars and each section comprising a rigid frame formed by a plurality of longitudinally arranged socketed bars rigidly connected by end pieces 115 carrying the journals for the section, each of said socketed bars having mounted therein a series of independent rectangular fuel bearing caps located above the frame and each held rigidly with relation to all of the other caps of the section, each cap having elongated downwardly flaring air admission openings therein and elongated downwardly flaring air admission edge slots, the edge 120 slots of each section being arranged opposite 125 unbroken edge of the adjacent section.

3. In a grate for burning fine fuel, the combination with the bearer bars, of dumping sections journaled in said bars, each section comprising a rigid frame formed by a 130

series of longitudinally extending parallel bars each having a series of elongated sockets therein and end pieces carrying journals on which the section is supported, each of 5 said socketed bars having rigidly mounted therein a series of substantially rectangular fuel bearing caps having edge slots and elongated air admission openings, said sections being spaced apart a distance substantially 10 equal to the width of the slots and openings and said slots and openings being distributed uniformly throughout the whole grate area, whereby air is admitted uniformly to all portions of the fuel carried by 15 the grate.

4. In a grate for burning fine fuel, a pivoted dumping section comprising a rigid frame formed by a series of parallel bars each having a series of equally spaced elong-

gated socket openings therein and a multiplicity of fuel bearing caps having flattened shanks seating in said socket openings, each of said fuel bearing caps being substantially rectangular on its fuel bearing face and each having elongated air admission openings extending through said face, the edges of each cap in proximity to the edge of an adjacent cap in the section being provided with air admission slots, whereby the air entrance openings are uniformly distributed without material reduction in the fuel supporting surface and the cumulative effect of edge growth in the sections is obviated. 20 25 30
